UNITED STATES PATENT OFFICE.

V. B. RYERSON, OF NEW YORK, N. Y.

SUBMARINE EXPLORER.

Specification of Letters Patent No. 21,852, dated October 19, 1858.

To all whom it may concern:

Be it known that I, VAN BUREN RYERSON, of the city, county, and State of New York, have invented new and useful Improvements 5 in Submarine Explorers; and I do hereby declare that the following is a full, clear, and exact description thereof, reference being had to the accompanying drawings, making part of this specification, in which—

10 Figure 1, is a perspective view of the explorer; and Fig. 2, a perspective sectional view representing the inside of the two halves as if the apparatus was cut in two by a vertical plane passing through the axis 15 and opened.

The same letters indicate like parts in the several figures.

The object of my invention is the production of an apparatus for submarine explorations by means of which persons may with safety descend to any required depth and remain there for a considerable length of time without communication or connection with the surface. And to this end the leading 20 character of my said invention consists in combining with the working chamber or chambers in which the explorers are to be placed, a reservoir containing air compressed to such an extent and in such quantity, and 25 so combined with the said working chamber or chambers that the explorers inside may draw the required supply from the said reservoir to suit their own demands for respiration and to control the buoyant or rising 30 power of the apparatus. And my said invention also consists in combining with the said working chamber or chambers, and said reservoir of compressed air, one or more ballast 35 chambers which by the explorers inside 40 can be made to communicate with the compressed air in the reservoir and with the surrounding water, so that air may be admitted to force out the water when it is required to increase the buoyancy of the apparatus to rise, or the water may be introduced to expel the air whenever it is desired 45 to increase the sinking power of the apparatus for the purpose of sinking. And my said invention also consists in purifying the 50 air inside the working chamber or chambers, whenever it has become vitiated by the respiration of the explorers inside, by a shower of water which in passing like spray through the vitiated atmosphere will absorb the carbonic 55 oxid or carbonic acid given out in respiration, while the said water will at the

same time give out the free atmospheric air known to be contained in considerable quantity in water. And my said invention also consists in combining with the working 60 chamber or chambers and with the reservoir of compressed air, a pump which communicates by means of its eduction pipe with the reservoir of compressed air and by means of a flexible induction pipe with the atmosphere 65 above the surface; the said flexible pipe for this purpose being provided with a float having a spring valve so regulated that it will be kept closed by the pressure of the water while rising to the surface, and opened 70 by the spring after reaching the surface of the water so that when required, in case of accident, by the working of the pump air may be drawn from the surface and forced 75 in the reservoir of compressed air, whenever, 80 from any cause, the supply forced in before sinking becomes insufficient.

In the accompanying drawings *a* represents the outer shell which I prefer to make of a cylindrical shape with a flattened dome 85 top. Within this there is an inner shell *v* of corresponding form with a space between the two which I denominate the compressed air chamber. Apertures are made at various suitable places and in corresponding 90 parts of the two shells to which are fitted tubes *c* extending from one shell to the other to which tubes are fitted suitable glasses *d* for the admission of light and exclusion of water. All the joints are to be made air 95 and water tight. The two shells at their lower end are properly secured to a strong metallic hollow ring *e* termed the ballast ring.

The space between the two shells is divided by an air tight horizontal partition *f*, a short distance above the ballast ring, to form two chambers *g* and *h*, the one *g* above the partition as before stated termed the compressed air chamber, and the other *h* 100 termed the ballast chamber, to aid the ballast ring in ballasting the apparatus under certain circumstances to be presently described.

The space inside the inner shell is divided 105 into two working compartments *i* and *j* by a horizontal floor *k* with a central hatchway *l* which can at pleasure be closed air tight by a hatch *m* to be secured in any suitable manner. A corresponding hatch way *n* is 110 formed through the dome of both shells connected by a cylindrical tube *o*; both ends

of the said tube being provided with cap or hatch *p*, *q*, connected by a screw bolt *r* for securing them to exclude water when sinking the apparatus. If desired the inside 5 may be divided into more than two compartments, but I deem two sufficient. the compressed air chamber communicates with the compartments *i* and *j* by means of two stop cocks *s* and *t* one above and the 10 other below the floor *k*, so that air can be let into either or both of the compartments at any time from the compressed air chamber or reservoir, but a greater number may be employed if desired. A communication 15 is formed between the compressed air chamber *g* and the ballast chamber *h* by means of a bent pipe *u* governed by a cock or valve. And a like communication is formed between the compressed air chamber *g* and the inside 20 of the ballast ring *e* by means of another bent pipe *v* also governed by a cock or valve. By means of another bent pipe *w* governed by a cock or valve the ballast chamber communicates with the surrounding 25 water; and by a similar pipe *x*, also governed by a cock or valve, the inside of the ballast ring communicates with the surrounding water. The pipes for forming these several communications extend within 30 the working compartment so as to have the several cocks or valves, by which they are controlled, within the convenient reach of the operators inside the working compartment. The continuosity of the inside of the 35 ballast ring *e*, and of the ballast chamber *h*, is interrupted by a vertical partition *y*. This partition is on one side of the communicating pipes above described, and on the other side of the partition the inside of the 40 ballast ring communicates with the surrounding water by a cock *z* near the bottom, and the ballast chamber *h* in like manner communicates with the surrounding water by a pipe *a'* near the bottom governed 45 by a cock or valve; but both the ballast ring and ballast chamber may be divided into any desired number of compartments to insure the balancing of the apparatus, in which case the several pipes and 50 cocks for the admission of air and water must be multiplied in the same proportion.

There is a pipe *b'*, governed by a cock which passes through the roof of both cases to the outside where it is bent to have its 55 discharged aperture at the lower end of the bent part, for the purpose of discharging air from the working chamber when it is desired to reduce the quantity of air in the working chamber to reduce the buoyant 60 power of the apparatus.

In the working chamber there is placed a rotary or other pump *c'*, with an induction pipe *d'*, extending down to the water, and a bent discharge pipe *e'*, having a spraying bulb *f'* at the discharge end—which dis-

charge pipe is connected with the pump by a swivel that the bulb may be moved to different parts of the compartment. The purpose of this is to discharge a shower of water near the top of the working chamber 70 that the particles of water in passing through the air of the compartment may absorb the noxious gases given out by the respiration of the operatives, and at the same time give out the free atmospheric air which 75 water is known to contain. There is also another pump *g'* in the working chamber with an eduction pipe *h'* leading into the compressed air chamber, and an induction pipe *i'* leading down near to the bottom to 80 which a flexible tube can be attached when desired. The other end of this flexible tube is to be provided with a float having a valve on its upper part which will open by a spring when it reaches the surface of the 85 water. The tension of the spring must be so regulated that while the float is rising through the water the pressure on the valve will keep it closed to prevent the entrance of water, but when the pressure is reduced 90 by reaching the atmosphere above, the spring shall force open the valve to admit air. The object of this part of the apparatus is, 95 in case of accident, or when by any circumstance the apparatus is required to remain below a longer time than usually required, the operators inside can get a new supply of air from the surface by attaching the flexible pipe passing the float under the lower edge of the ballast ring, that it may 100 rise to the surface, and then working the pump to take in a fresh supply of air.

The apparatus constructed as above described is to be operated in the following manner, viz.—Air is to be forced into the 105 compressed air chamber to a considerable density, say to about four hundred pounds to the square inch, and water excluded from the inside of the ballast chamber and ballast ring, and sufficient pressure of air let into 110 the working chambers so that the apparatus will float with the dome above the surface. In this condition the hatch *m* in the floor is closed air tight, and then the hatches *p*, *q*, in the top, can be opened to take into the 115 apparatus whatever may be required; the compressed air below the floor maintaining the buoyancy of the apparatus so that it floats like a boat on the surface. The hatches *p*, *q* in the dome are then closed, and air admitted from the compressed air chamber into the upper working chamber to about the same density as in the lower working chamber so that the hatch in the floor *k* 120 can be opened without shock. In this condition the apparatus will not sink; but when it is desired to sink the two communications between the ballast ring and the surrounding water are opened, in consequence of 125 which water will enter through the lower 130

one and air escape through the upper one, and as this takes place the specific gravity of the whole apparatus with its contents is increased and it begins to sink. When the 5 whole of this chamber is filled with water the two cocks are to be closed, but it will be perceived that the rapidity with which the substitution of water for air is to take place is entirely under the control of the operators by means of the cocks, and hence the 10 sinking of the apparatus may be as gradual or quick as may be desired. When more sinking power is required the same thing is to be done with the ballast chamber, the admission of water to that chamber increasing 15 still further the sinking power of the apparatus. As the apparatus sinks, and the pressure of the superincumbent column of water is thereby increased, the density of 20 the air in the working chambers must be increased in proportion or the water would enter from below to too great a height in the working chambers, and it will be seen that the operators inside have perfect control of 25 this by simply opening either one of the cocks leading into the compressed air chamber.

When at any time it becomes necessary to develop the buoyant or rising power to elevate the apparatus, the communication between either the ballast chamber or the ballast ring, or both, with the surrounding water is to be opened, and also the communication with the compressed air chamber to 35 admit compressed air and thereby force out the water, which renders the apparatus buoyant; or this can be done by increasing the density of the air in the working chambers. In this way the apparatus can, with 40 the greatest ease, and at the will of the operators inside, be maintained at any desired depth, or be made to sink deeper, or to rise, and all this without communication with the surface.

45 After completing any operation below, and before reaching the surface, it is best to transfer all articles from the working shelf *j* to the floor *k*, and close the hatch *m*, and then the pressure of air in the upper 50 working chamber can be relieved through the discharge pipe *v'* so that when reaching the surface the hatches in the dome or top can be opened to the atmosphere. Care must be taken in rising not to develop the 55 buoyant power of the apparatus too rapidly, as the apparatus can be made to rise at a dangerous velocity. And it will also be observed that the pressure of the air in the working chambers should be gradually 60 reduced as the apparatus rises to the surface to correspond with the decreasing pressure of the column.

When operating below whenever the operators find that the air in the working 65 chambers becomes too much vitiated by

respiration the pump *c'* is to be operated to discharge a shower or spray from the bulb, which shower falling through the atmosphere of the compartments causes the particles of water to absorb the noxious gases 70 contained in the air, while the water at the same time gives out the free atmospheric air which it contains. In this way by occasionally producing artificial showers through the atmosphere of the working chambers to 75 carry off the noxious gases the operators are thereby enabled to consume all the oxygen contained in the air together with that contained in the free atmospheric air given out by the water. After the oxygen has been 80 sufficiently consumed the air is to be renovated in the working chambers by drawing a fresh supply from the compressed air chamber; in this way the apparatus can remain a long time under water without danger or serious inconvenience to the operatives inside.

In case of danger the operatives have the means within the apparatus of rising to the surface as rapidly as they may desire; and 90 if it should be desired to remain under water longer than contemplated by the supply of air in the compressed air chamber, by sending the float, on the end of the flexible pipe, to the surface, and operating the pump *g'* the supply of air can be renewed at 95 pleasure without the necessity of raising the apparatus; but the use of this part of the apparatus will be of rare occurrence as one charge of air will be ample for the length 100 of time usually required for any one submarine exploration.

Care should be taken never to permit the pressure of the air in the compressed air chamber to get down to the pressure in the working chambers, for in that case it would become impossible to impart the required buoyant power to the apparatus for rising, as the water can only be expelled from any 105 part of the apparatus by air under a tension greater than the pressure of the superincumbent column of water; and in the event of neglecting this precaution it would become necessary to restore the required 110 preponderance of pressure in the compressed air chamber by sending the float to the surface and working the pump *g'* as before described.

The action of any and all means heretofore employed for forcing the required supply of air in the working chamber from the atmosphere above produces vibrations within the apparatus, which vibrations under the pressure required to exclude the water 115 at considerable depths produce violent actions on the human system, inducing bleeding at the nose and ears, and generally a painful sensation throughout the system. This is entirely avoided in my improved plan as the vibrations are entirely avoided, 120 125 130

there being no pumping operation required for any of the operations, except when it becomes necessary to remain below a greater length of time than was anticipated, and 5 then the pumping in of air is not in the working chambers but in the compressed air chamber and therefore not injurious to the operators.

Any strength given to the apparatus 10 which will resist in the open air the pressure to which the air is to be compressed in the apparatus will be perfectly safe under water because the submersion of the apparatus tends to equalize the pressures outside and inside.

I do not wish it to be understood that I 15 limit my claim of invention to the special form and construction herein specified, as these may be greatly varied within the 20 range of my said invention, so long as the principle or character of my invention is retained.

What I claim as my invention, and desire 25 to secure by Letters Patent, is—

1. The method of controlling the rising and sinking power of the apparatus by 30 means of a reservoir or reservoirs of compressed air connected and combined with a working chamber or chambers and rising and sinking therewith, substantially as described, so that the operators within, by the use of the compressed air can readily control the rising and sinking power of the apparatus without communication with the 35 surface, substantially as set forth.

2. I also claim in a submarine explorer 40 in which the rising and sinking power is controlled by a reservoir or reservoirs of compressed air making part thereof and rising and sinking therewith and in which there are two or more working chambers, substantially as described, the dividing the said working chambers by a hatch way which can be closed water and air tight

substantially as described, to sustain the apparatus with the top above water when the said top is open for any purpose, as set forth.

3. I also claim in combination with the reservoir or reservoirs of compressed air 50 connected and combined with one or more working chambers, and rising and sinking therewith, substantially as described, the employment of one or more ballast chambers at or near the bottom, and so arranged, 55 substantially as described, that at the will of the operators, they can be made to communicate with the compressed air reservoir or reservoirs, and with the surrounding water, as described, to increase the lifting 60 or sinking power of the apparatus, as set forth.

4. And I also claim in a submarine explorer combining with the working chamber or chambers thereof the employment of a 65 spray or shower of water, which at the will of the operators inside may be discharged at any time required to purify the air by absorption, substantially as described.

5. And I also claim in combination with 70 the reservoir or reservoirs for compressed air, combined and moving with one or more working chambers, the employment of a pump which can be worked by the operators within, and which communicates with the 75 reservoir or reservoirs of compressed air, and also, by means of a flexible pipe and float provided with a self acting valve, with the atmosphere above substantially as described, so that in case of accident the operators within can replenish the air in the reservoirs to enable them to control the apparatus, as described.
